UNITED STATES PATENT OFFICE.

WILLIAM A. SCHLEICHER, OF CLEVELAND, OHIO, ASSIGNOR TO THE EBER-HARD MANUFACTURING COMPANY, OF CLEVELAND, OHIO, A CORPORATION OF OHIO.

BUCKLE.

No. 850,795.

Specification of Letters Patent.

Patented April 16, 1907.

Application filed June 14, 1906. Serial No. 321,630.

To all whom it may concern:

Be it known that I, WILLIAM A. SCHLEICHER, of Cleveland, Cuyahoga county, Ohio, have invented a new and useful Improvement 5 in Buckles, of which the following is a full, clear, and exact description, reference being had to the accompanying drawings, forming part of this specification, in which—

Figure 1 is a plan view of a buckle embodying my invention. Fig. 2 is a section on the line II II of Fig. 1.

The object of my invention is to provide an efficient buckle whose frame can be readily shaped or formed from a single piece of wire 15 at a low cost.

In carrying out my invention I take a single piece of wire of the proper size and bend the end portions thereof to form, respectively, the tuck-loop 2 and the buckle-loop 3, the intermediate portion of the wire forming an oblique transverse connection 4 between the two loops, which forms a carrier for the

tongue 5, and against the opposite sides of which the free end portions 6 of the wire are fitted and secured by tinning or soldering. 25 By this construction the frame is strongly braced and may be readily shaped at a low cost.

What I claim is—

A buckle having its frame composed of a 30 single piece of wire, whose end portions are bent to form tuck and tongue loops respectively, and whose intermediate portion forms a transverse oblique connection between said loops, the free ends of the wire being fitted 35 and secured to the opposite oblique sides of the said connection, and a tongue carried by said connection; substantially as described.

In testimony whereof I have hereunto set my hand.

WILLIAM A. SCHLEICHER.
